UNITED STATES PATENT OFFICE.

FREDERICK C. GOODWIN, OF LOUISVILLE, KENTUCKY, ASSIGNOR TO MODERN CONSTRUCTION COMPANY, OF LOUISVILLE, KENTUCKY, A CORPORATION OF KENTUCKY.

APPARATUS FOR FORMING MOLDS.

1,133,020.

Specification of Letters Patent. Patented Mar. 23, 1915.

Application filed September 6, 1912. Serial No. 718,908.

To all whom it may concern:

Be it known that I, FREDERICK C. GOODWIN, a citizen of the United States, residing at Louisville, in the county of Jefferson and State of Kentucky, have invented certain new and useful Improvements in Apparatus for Forming Molds; and I do hereby declare the following to be a full, clear, and exact description of the invention, such as 10 will enable others skilled in the art to which it appertains to make and use the same.

This invention relates to apparatus for forming molds to be used in the manufacture of concrete bricks or other castings.

15 One object of the invention is the provision of improved apparatus adapted to simultaneously form a plurality of cavities or impressions in a plastic or melted mass, to congeal or harden said mass around the cavities or impressions while the cores are in the mass, and to remove said cores without injuring the mold thus formed.

20 Another object is to completely form a multiple cavity mold, resembling one side of a honeycomb, directly in the receptacle or container for the plastic or melted mass, said receptacle or container serving as an outer mold and thus dispensing with separate outer mold walls such as are generally used 25 in conjunction with the cores.

The invention will hereinafter be first 30 fully described with reference to the accompanying drawings, which form a part of this specification, and then pointed out in the 35 claims following the description.

In the drawings: Figure 1 is a perspective view of the apparatus, showing the cores ready to be pressed into the plastic or melted mass. Fig. 2 is a perspective view illustrating 40 the arrangement of the apparatus after the cores have been withdrawn from the mass, some of the cores having been removed, to more clearly show the construction of the lower or stripper frame. Fig. 3 is a transverse vertical section of the apparatus with 45 the cores pressed into plastic mass. Fig. 4 is a fragmentary horizontal section through the lower frame and cores. Fig. 5 is an enlarged detail view of one of the cores, showing 50 more clearly how they are suspended from the parallel flexible strips of the upper frame, and also illustrating the piping for the cooling or freezing agent.

55 Referring to the drawings by letters of reference, A designates a receptacle or con-

tainer for the plastic or melted mass M, such as paraffin. The shape and size of the container may conform to the number, shape, size and spacing of the cores. Suitably supported above said container are a plurality 60 of cores B suspended from an upper frame C and projecting through a lower frame D.

The upper frame consists of a plurality of parallel longitudinal strips E, preferably made of flexible metal, with their ends suitably secured in transverse end pieces F, as by lugs or tenons e on the ends of said strips engaging longitudinal grooves or channels f in the end pieces. Said longitudinal strips are provided with openings or perforations e' 70 into which pins or projections b on the upper end portions of the cores are loosely fitted for suspending or supporting said cores. It will readily be seen that the strips E 75 separate adjacent sides of the cores. The ends of said cores are spaced apart by separators b', one of which may be provided on the end of each core, so that each core is separated or spaced all around from the adjacent cores. The outer edges of the separators, which edges contact with the adjacent cores for positively spacing said cores apart, 80 may be tapered, as illustrated in Fig. 5, so as not to interfere with the cores being rocked slightly in withdrawing them from the finished mold to prevent breaking the latter, as 85 hereinafter explained.

The lower frame D may be constructed in a similar manner to the upper frame, and comprises a series of longitudinal strips d 90 and end pieces d'. The lower frame, however, is not connected directly to the cores but is free to move up and down around them with the strips d working in the spaces between the sides of said cores. The end pieces of both frames are preferably made of heavier metal than the longitudinal strips, in order to support the latter in the channels of said end pieces under the stress 95 to which the device is subjected in operation. Said end pieces may be held in proper relation to their longitudinal strips by tie-rods c and d' on the upper and lower frames, respectively.

The two frames are adjustably connected 100 in any suitable manner, whereby one may be moved vertically with respect to the other in order to withdraw all of the cores at once. As illustrated, this connecting means may consist of a system of vertically disposed 105 110

screws G, one arranged near each corner of the frames and working in smooth bored lugs H secured to the upper frame and internally screw-threaded lugs I fastened to 5 the lower frame. The upper ends of said screws are equipped with mitered pinions g which mesh with other mitered pinions k on shafts K carrying cranks L. Obviously, the turning of the cranks will actuate the 10 screws G and cause the lower frame to move up or down with respect to the upper frame, according to the direction of rotation of said cranks.

Each of the cores B is adapted to be 15 cooled or chilled in order to congeal or harden the plastic mass M in the container or receptacle A. For this purpose, said cores may be made hollow, as illustrated in Figs. 3, 4 and 5, and have a pipe N for a 20 cooling or freezing agent extending into the interior thereof. It will be understood, however, that any other suitable means for chilling the cores may be employed.

In the operation of the apparatus it is optional whether the receptacle or container A be raised to insert the cores into the plastic mass, or whether said cores be lowered into the receptacle. For the purpose of explanation, it may be understood that the two 30 frames with the cores are suspended or supported in any suitable manner, as by the hangers P depending from a fixture and attached to the upper frame, and that the receptacle is placed upon a platform R 35 adapted to be raised and lowered by any known means which it is deemed unnecessary to illustrate. Supposing then that the receptacle and cores are supported as just described and arranged as shown in Fig. 1, and that a requisite quantity of melted paraffin or other plastic mass M is contained 40 in said receptacle, the raising of the latter will cause the cores to be inserted into said mass as illustrated in Fig. 3. The cores, being chilled, will cause the paraffin or plastic mass to harden around them in the container, thereby forming a multiple cavity mold as shown in Fig. 2. After the mass has become sufficiently hard, which is 45 accomplished very quickly, the receptacle or container is lowered, the lower frame B being lowered simultaneously until the mold is entirely removed or stripped from the cores. The lower frame being in contact with the 50 upper surface of the hardened mass positively retains it in the container as the cores are withdrawn from said mass. The receptacle or container may then be moved away from the device and is ready for casting the 55 concrete bricks or other articles in the multiple cavity mold thus formed in the hardened mass. After the bricks or other articles are cast, the mold may be readily removed by melting.

It will be noted that the lugs or projections b on the cores have a slight movement in the openings e' in the longitudinal strips of the upper frame. This slight movement enables the print or mold to be made perfect in shape without danger of breaking said 70 mold when withdrawn. It will also be seen that on account of the flexibility of the longitudinal strips of the frames and the manner of suspending the cores from the upper frame, said cores may be readily removed 75 when necessary or desirable for repairs or other purposes, and yet, when in place, said cores are held securely against accidental displacement.

While the apparatus herein illustrated 80 and described is designed particularly for forming paraffin molds to be used in the manufacture of concrete bricks, I do not desire to limit the invention in its application to any special kind of molds, inasmuch 85 as the same apparatus may be employed for forming molds of other plastic or meltable materials for various purposes. It should also be understood that a mold with a single cavity or impression may be made with this 90 apparatus, as well as a multiple cavity mold, by simply using a single core and correspondingly shaped container for the plastic mass. Moreover, the shape of the cores may be varied as desired subject to the limitation 95 that their side and end walls must not be inclined outwardly and downwardly for, if they were, it would be impossible to withdraw said cores without mutilating the 100 mold.

The plastic or melted mass referred to herein should be construed to cover any soft mass which is adapted to be hardened by a change of temperature as, for example, melted paraffin which may be hardened by cooling.

As best illustrated in Fig. 5, each of the cores B may have one supporting pin b on one side and two of said pins on the other side; and the strips E of the upper frame 110 be provided with openings e' corresponding in number and arrangement to said pins. Accordingly, the intermediate strips E, two of which are shown in Fig. 5, are provided with three openings opposite each core, the 115 core at one side of each strip having one pin entering the middle opening and the core at the opposite side having two pins entering the other two openings.

Having thus described my invention, what 120 I claim as new and desire to secure by Letters Patent is:

1. In apparatus for forming paraffin molds to be used in the manufacture of concrete bricks and the like, the combination 125 with a container for soft paraffin, of a plurality of cores spaced apart and adapted to be simultaneously inserted into and simul-

taneously withdrawn from the paraffin mass in the container, cooling means in the cores for hardening the mass around and between the cores while they are in the container, and 5 means movable toward and away from the container and adapted to remain in contact with the outer edge of the hardened mass when the cores are withdrawn therefrom leaving said mass in the container in the 10 form of a multiple cavity mold for the purpose specified.

2. In apparatus for forming paraffin molds to be used in the manufacture of concrete bricks and the like, the combination with a 15 container for soft paraffin, said container having a substantially flat internal bottom surface, of a plurality of cores spaced apart and adapted to be inserted into and withdrawn from the paraffin mass in the container, the mass filling the spaces between said cores when the same are inserted into it, and means arranged in said cores for changing the temperature thereof to cause the 20 mass around and between them to harden and form said mass into an integral multiple cavity mold, the adjacent cavities of which have common separating walls.

3. In apparatus for forming paraffin molds to be used in the manufacture of concrete bricks and the like, the combination with a 30 container for soft paraffin, of a frame having a series of strips arranged side by side, a plurality of cores suspended between and spaced apart by said strips, a lower frame also having a series of strips extending between said cores, means for moving the cores and both frames together toward the container for pressing the cores into the 35 paraffin mass therein, and means for moving the cores and upper frame away from the container while the lower frame is retained in contact with the outer edge of the mass, and cooling means in the cores for hardening the mass when said cores are pressed into 40 the same.

4. The combination with a frame having a series of flexible strips arranged side by side and provided with openings in their vertical faces, of a plurality of cores having pins engaging said openings, for suspending 50 said cores between said strips, said pins being removable from said openings when the flexible strips are forcibly spread apart.

5. The combination with a frame having a series of strips arranged side by side, of a 55 plurality of cores suspended between each pair of adjacent strips, and separators mounted on the cores and extending between them to contact with the outer surface of adjacent cores for positively spacing the 60 cores apart along the strips, at the same time leaving said cores separate and independent of one another.

6. The combination with a frame having a series of strips arranged side by side, of a 65 plurality of cores suspended between each pair of adjacent strips, and integral separators on the cores and extending into contact with the outer surface of adjacent cores for positively spacing them apart along the 70 strips, at the same time leaving said cores separate and independent of one another.

7. The combination with a frame having a series of strips arranged side by side, of a 75 row of cores loosely suspended between each pair of adjacent strips, and separators mounted on the cores and extending between them to contact with adjacent cores for positively spacing them apart along the strips, said separators having their outer 80 contacting edges tapered to permit the cores to be rocked slightly for the purpose specified.

In testimony whereof I affix my signature in the presence of two witnesses.

FREDERICK C. GOODWIN.
